UNITED STATES PATENT OFFICE.

HAROLD E. HOUSEMAN, OF WILMINGTON, DELAWARE, ASSIGNOR TO STANDARD-TRUMP BROTHERS MACHINE COMPANY, OF WILMINGTON, DELAWARE, A CORPORATION OF DELAWARE.

CIRCULAR-KNITTING MACHINE.

Application filed January 13, 1925. Serial No. 2,082.

The object of my invention is to provide, for application to a circular knitting machine for knitting stockings, mechanism whereby so-called lace work may be formed on any desired part of the stocking and particularly around the leg and on top of the foot.

An ordinary method of producing lace work is by means of tuck stitching. In plain knitting with latch needles, a needle, at each rotation of the machine, is lifted high enough to enable its latch to clear the loop formed by such needle in the previous course of knitting. To form a tuck stitch, the needle, in one or more successive courses, is not lifted high enough for its latch to clear the loop, which is retained until, on the next course, the latch rises high enough to clear the plurality of loops that it holds, which loops, on the descent of the needle, are cast off. Tuck stitching of this character may be effected by providing the tuck stitch needles with long latches that will not clear the loops when such needles are raised to the same height as the needles provided for plain stitching; or by making the latches of the tuck stitch needles of the same length as the latches of the needles that are to do plain knitting and lifting the needles to different heights, the tuck stitch needles not rising high enough, on the tuck stitching courses, to clear the loops. If the tuck stitch needles are to be raised to variable heights, they are usually provided with special butts operable by a special cam or cams controlled by special actuating mechanism.

My invention contemplates no different principle of operation of producing tuck stitching from that heretofore known, but it exhibits features of novelty, which may be summarized as follows: (1) The provision of a novel arrangement of regular and special (tuck stitch) needles, comprising all the needles of the front and rear bank, characterized by four sets of needles each having a latch or butt different, with respect to their relative lengths, from those of any other needle of the set and adapted to be actuated by a single cam. (2) The provision of a single novel cam whose position may be so shifted as to control the actuation of all the needles to produce at will, plain stitching on the front and rear needles, plain stitching on the rear and tuck stitching on the front, or

tuck stitching on both front and rear. (3) Novel mechanism, between the pattern chain and the special cam, for controlling the position of the cam. (4) The substitution of the special cam for the regular needle-lifting cam and the substitution of the pattern-controlled cam-actuating mechanism for the regular pattern-controlled cam-actuating mechanism; thereby avoiding the provision of a special cam, and special actuating mechanism therefor, for actuating tuck stitch needles, in addition to the regular needle-lifting cam and cam-actuating mechanism; whereby a distinct simplification in the machine is effected.

A preferred embodiment of the invention is shown in the accompanying drawing, in which—

Fig. 1 is a plan view of a part of the knitting machine comprising the pattern-controlled mechanism for actuating the needle-lifting cam, partly broken away.

Fig. 2 is a side elevation of the same, with parts omitted.

Figs. 3 and 3^a are detail views of parts of pattern chains, showing different arrangements of lugs thereon.

Fig. 4 is a face view of the knitting cams, developed.

Fig. 5 is a radial sectional view of the needle-lifting cam, the slide by which it is carried and the spring for actuating the slide.

Fig. 6 is an elevation of the different forms of needles.

Fig. 7 is a diagram showing the different heights occupied by the different needles in different positions of the needle-lifting cam, two of the three needles being slightly tilted from their true vertical position in order to clearly illustrate such different vertical positions.

Fig. 8 is a diagram of the two banks of needles illustrating one of many permissible arrangements of regular and tuck stitching needles.

Fig. 9 is a diagram illustrating a stocking and the relative positions of the different sets of needles while knitting the various parts thereof.

The regular needles *a* of the front bank (which, with needles *b*, knit the front of the leg and top of the foot) may be provided with latches of normal length, although I

shall refer to them as short latch needles to distinguish them from the long latch needles hereinafter described. The needles *a* are provided with long butts.

5 The special (tuck stitch) needles *b* of the front bank are provided with long latches and with long butts.

The regular needles *c* of the rear bank (which, with needles *d*, knit the rear of the 10 leg, the heel, the bottom of the foot and the toe) are provided with short latches (corresponding in length to the latches of needles *a*) and with butts of medium length.

15 The special (tuck stitch) needles of the rear bank are provided with short latches and with short butts.

The regular set of knitting cams *e* is shown in Fig. 4. In place of the regular needle lifting cam is substituted a special 20 needle lifting cam *f*. Cam *f* is provided with two cam surfaces located side by side: one a low surface *g* that may be flat along the greater part of its length; the other a high surface *h* that may have the form of 25 a lump or swell. This cam is movable radially (its position being controlled by pattern-controlled mechanism to be hereinafter described), into three different positions, which I shall call its inner, outer and middle or intermediate positions.

30 When the cam *f* is in its inner position (see Fig. 7), its low surface *g* is in line of travel of the short and medium butt needles, while its high surface *h* extends sufficiently far in, radially, to be engaged by the long butts of needles provided with long butts. Hence, the regular needles *a* of the front bank and the special needles *b* of the front bank will be lifted to a higher level 35 than the regular needles *c* of the rear bank and the special needles *d* of the rear bank. Inasmuch, however, as the needles *c* and *d* have short latches, their latches will be raised high enough to clear the loops of 40 the previous course; the latches of needles *b*, notwithstanding their greater length, are raised sufficiently high to also clear the loops. Needle *a* is raised substantially higher than is necessary for its latches to clear 45 the loops, but this excess degree of lift does no harm.

50 It will, therefore, be understood that when the cam *f* is in its inner position, all the needles will operate to produce plain stitching, as is desirable or necessary in knitting the welt *t* of the stocking, and also a short section *y* of the foot adjacent the toe. See I, Fig. 9.

55 When the cam *f* is moved to its outer position, the high surface *h* is not in line of travel of any of the butts; the low surface *g* is in line of travel of long and medium butts; while the cam is so far out that the short butt needles ride inside the cam. All the regular needles *a* of the front

bank and *c* of the rear bank, being provided with the short latches, are raised sufficiently high to allow their latches to clear the loops. The special needles *b* of the front bank, although raised as high as needles *a* and *c*, are not raised high enough to enable their long latches to clear the loops. The special needles *d* of the rear bank are not raised at all, and their latches, also, fail to clear the loops. Hence needles *b* and *d* operate 70 as tuck stitch needles, and tuck stitching is produced (see II, Fig. 9) on the front and rear of the leg *u* of the stocking. It will be understood, of course, that during the knitting of the leg the cam *f* will occupy its outer position only during a limited number of courses (say two) and will then be shifted to its inner position for a limited number of courses (say two, six or ten) to allow the special needles to do plain knitting. 75

80 When the cam *f* is moved to its median position, the high surface *h* is not in line of travel of any of the butts; but the low surface is in line of travel of all the butts. The regular needles *a* and *c* of the two 85 banks and the special needles *d* of the rear bank, being all provided with short latches, are all raised high enough to enable their latches to clear the loops, and the special needles *d* function, like the regular needles *a* and *c*, to make plain stitches; but the special needles *b* of the front bank, being provided with long latches, are not raised high enough for their latches to clear the loops, and these act to tuck stitch. The cam occupies this median position during the knitting of the extreme lower part *v* of the leg 90 and during the knitting of the foot *w* (see III and V, Fig. 9).

95 During the knitting of the heel *w* and toe 100 *z*, the needles of the front bank are moved up out of action. The cam *f* may then occupy either its inner or median position (the inner position is shown at IV and VI, Fig. 9), because in either position the special 105 needles *d* of the rear bank operate to do plain stitching.

110 The special pattern-controlled mechanism for moving the cam into its three specified positions will now be described.

115 The main driving shaft 10 of the machine carries a bevel gear 11 which engages a bevel gear 12. The sizes of the two gears are such that at each rotation of the shaft 10, the gear 12 turns one quarter of a revolution. The shaft of gear 12 carries an eccentric 13 and a collar 23 on which may be secured one, two or three cam pieces 24, each extending ninety degrees around the shaft of gear 12. A yoke 14 embraces the eccentric 13. The yoke is carried on an arm 15, whose hub is rockable on a post 16. The hub of rock arm 15 also carries a pawl arm 17, which is adapted to engage and turn a ratchet wheel 18 sleeved on the shaft 10 and 120

carrying a sprocket wheel 19 for the pattern chain 20. Reference is made to the H. E. Houseman Patent No. 1,364,112, dated January 4, 1921, for a more particular illustration (see Figs. 1 and 3) and description of the means for actuating the pattern chain sprocket 19. For the purpose of describing the present invention, it is sufficient to note that the gear wheel 12 makes one complete 10 rotation to every four courses of knitting, that the ratchet 18 is actuated once in each complete rotation of gear 12, and that at each actuation of the ratchet 17, the pattern chain 20 is advanced a distance of one-third of a 15 link.

Secured to the machine frame is a stud 25, to which is pivoted a short arm 26. On this arm is pivoted between its ends a lever 27, opposite ends of which are in line of 20 travel of the cam pieces 24 and the high lugs 21 and low lugs 22 carried by the links of the pattern chain.

The special cam *f* is carried by a slide *i*, 25 slidably radially of the knitting head, in guides *j*, and normally held in its inner position by means of a spring *k*. It is moved out to its median position or to its outer position by means of a rod 28, which is adjustably secured to the swingable end of the 30 short arm 26.

When one end of lever 27 is opposite a space between lugs of the pattern chain, it is functionless. That is, in this position, the engagement of its other end by cam 24 merely 35 causes lever 27 to be rocked on its central pivot, effecting no movement of lever 26.

When lever 27 is opposite a low lug 22 of the pattern chain, the engagement of 40 lever 27 by cam 24 will rock the lever on lug 22 as a fulcrum and turn arm 26 so as to pull rod 28 to move cam *f* to its median position.

When lever 27 is moved opposite a high lug 21 of the pattern chain, the engagement 45 of lever 27 by a cam 24 will rock the lever on lug 21 as a fulcrum and pull rod 28 to move cam *f* to its outer position.

As soon as cams 24 travel beyond lever 50 27, spring *k* returns cam *f* to its inner position.

Bearing in mind, as above stated, that the cams 24 bodily turn about their axis once to every four courses of knitting, it will be understood that if there are no lugs on the 55 pattern chain, cams 24 will be functionless, and cam *f* will occupy its inner position, dictating plain knitting on all the tuck stitch needles.

If the pattern chain should be provided 60 with a continuous succession of long lugs, as shown in Fig. 3, then cams 24 will cause cam *f* to be moved into its outer position and to be held there during two courses of knitting. It will then release cam *f* and allow it to be returned by its actuating spring 65

into its inner position during two courses of knitting. This will cause the special needles of both the front and rear banks to operate to tuck stitch, and will produce lace work entirely around the fabric, as in knitting the leg. The optical effect will be that of continuous lace work. 70

If the pattern chain should be provided, at another part of its length, with a continuous succession of short lugs, as shown in Fig. 3, then cams 24 will move cam *f* into 75 its median position and hold it there during two courses of knitting and then release cam *f* and allow its actuating spring to return it to its inner position during two courses of knitting. This will cause the special needles of only the front bank to tuck stitch, and will produce lace work, of a continuous effect, on one-half the fabric and plain knitting on the other half of the fabric; as in 80 knitting the foot between the heel and toe. 85

It will be understood that a fabric may be produced with courses of circumferential lace work separated by a variable number of courses of plain stitching by suitably 90 spacing apart the lugs on the pattern chain.

Bearing in mind that cams 24 make one bodily rotation to each ratcheting of the pattern chain, and that each ratcheting of the pattern chain advances the chain a distance of one-third of a link, it will be understood that if the lugs are so spaced apart, as shown in Fig. 3, that between each two adjacent lugs there is a space equal to the length of a lug (that is, two lugs on the end of one link, one lug in the middle of the next link, and so on), cams 24 will be effective to operate cam *f* only at alternate revolutions; so that the special needles will operate as tuck stitch needles for two courses 100 and will then operate as regular needles for six courses; producing in the fabric the effect of spaced apart courses of tuck stitching. 105

So far as concerns the mechanism shown in Figs. 1, 2 and 3, it is clear that it might be readily modified without departing from the invention: although there are obvious advantages in the specific construction involving a lever pivoted between its ends on a normally stationary pivot, but which may swing, on the lugs 21 or 22, or a cam 24, as a fulcrum, to alter the position of its intermediate pivot and thereby actuate the needle-lifting cam. It will be understood that any known type of pattern mechanism may be substituted for the pattern chain. 115 120

Where in the claims I speak of a cam adapted to control the vertical positions of needles, I mean the expression to be broad enough to cover the maintenance of the short butt needles *d* in a depressed position by the movement of the cam *f* into its outer position. 125

Having now fully described my invention, 130

tion, what I claim and desire to protect by Letters Patent is:

1. In a circular knitting machine, the combination with two semi-circumferential banks of needles provided with butts and latches, one bank containing regular needles and tucking needles differing from each other with respect to length of latch and the other bank containing regular needles and tucking needles differing from each other with respect to length of butt, of a needle-lifting cam adapted to be shifted into different positions and thereby control the relative vertical positions of the needles to respectively cause one, neither, or both of the sets of tucking needles to form tuck stitches while the regular needles are forming plain stitches. 70
2. In a circular knitting machine, the combination with front and rear banks of needles provided with latches and butts, each bank comprising regular needles and tuck stitch needles, the tuck stitch needles of the two banks being structurally differentiated from the regular needles and also structurally differentiated from each other with respect both to length of butts and length of latches, of a needle-lifting cam adapted to be moved into three different positions and in said positions to respectively control the relative vertical positions of the four sets of needles so as to cause respectively one, both and neither of said sets of tuck stitch needles to lift to the height required to cause them to function as regular needles. 75
3. In a circular knitting machine, the combination with front and rear banks of needles each comprising regular needles and tuck stitch needles, the tuck stitch needles of the two banks being structurally differentiated from each other and from the regular needles, of a single needle-lifting cam provided with two cam surfaces of different height and adapted to be moved into a plurality of different positions and in said positions to control the relative vertical positions of the four sets of needles so as to cause the two sets of regular needles to effect plain stitching and two sets of tuck stitch needles to both effect plain stitching or tuck stitching or one set to effect plain stitching and the other tuck stitching. 80
4. In a circular knitting machine, the combination with two sets of needles provided with butts and latches and adapted to knit respectively the front and back of a stocking, each set of needles containing regular needles and tuck stitch needles, the tuck stitch needles of the two sets being structurally differentiated from the regular needles and also structurally differentiated from each other with respect both to length of butts and length of latches, the tuck stitch needles operating to clear loops when raised to a given height and to hold loops when not raised to such height, and a single cam provided with two cam surfaces of different heights and movable into a plurality of positions and adapted in such positions to differentially control the vertical positions of the tuck stitch needles so as to cause one set, both sets or neither set of tuck stitch needles to be lifted to the height required to clear loops. 85
5. In a circular knitting machine, the combination with four sets of needles having butts of three different lengths and latches of two different lengths, of a needle-lifting cam adapted to actuate the butts of all the needles and to be shifted into different positions relative to said butts to control the relative vertical positions of two of said sets of said needles to respectively cause them both to tuck, both to plain stitch and one to tuck and one to plain stitch. 90
6. In a circular knitting machine, the combination with two semi-circumferential banks of needles, one bank comprising regular needles each with a relatively short latch and a relatively long butt and special needles each with a relatively long latch and a relatively long butt, the other bank comprising regular needles each with a relatively short latch and a butt of medium length and special needles each with a relatively short latch and a relatively short butt, of a needle-lifting cam provided with two cam surfaces of different height and movable into three different positions, in one of which the long butt needles are adapted to ride on the higher surface and the other needles on the lower surface, in another of which all the butts are adapted to ride on the lower surface, and in another of which the long and medium butt needles are adapted to ride on the lower surface while both surfaces are out of line of travel of the short butt needles. 95
7. In a circular knitting machine, the combination with different sets of needles and a movable needle-lifting cam adapted in different positions to control the lifting of the needles of the several sets to different relative heights, of a driving shaft, a second cam, a pattern chain, means actuatable by the driving shaft to continuously rotate the second cam and intermittently advance the pattern chain, the pattern chain comprising lugs of different heights, a lever one part of which is directly operable by the second cam and another part of which is in line of movement of the pattern lugs, said lever being swingable on a normally stationary point but bodily movable away from said point when concurrently operated by the second cam and a pattern chain lug, and means connecting said lever with the needle-lifting cam, whereby, when said lever is so bodily moved, the needle-lifting cam is moved from a normal position to different distances dependent on 100

the height of the lug with which said lever coacts.

8. In a circular knitting machine, the combination with two sets of needles adapted
5 to knit respectively the front and back of a stocking, each set of needles containing tuck
stitch needles, a needle-lifting cam adapted
in different positions to differentially actuate
the front and back tuck stitch needles so as
10 to cause respectively one, both and neither
of them to form tuck stitches, a driving
shaft, a second cam, a pattern chain, means

actuatable by the driving shaft to continuously rotate the second cam and intermittently advance the pattern chain, and means 15 concurrently actuatable by the pattern chain and the second cam to shift the needle-lifting cam to different distances from its normal position.

In testimony of which invention, I have 20
hereunto set my hand, at Philadelphia,
Pennsylvania, on this 30th day of December,
1924.

HAROLD E. HOUSEMAN.
